E. L. Jones

UNITED STATES PATENT OFFICE

LUTHER M. JONES, OF CHICAGO, ILLINOIS

UTILITY STAND

Application filed January 16, 1928. Serial No. 247,080.

My present invention relates to tables, stands and other similar supports and has more particular relation to a handy stand or table that may be placed in proper relation 5 to a bed or chair to receive a book, magazine or the like, so that it is in a convenient position for the reader, or may be adjusted to a level position for supporting dishes or other articles, or may be used for a music stand for 10 musicians. In fact there are a great many uses to which the present device may be put and I do not limit its use to those herein mentioned.

The device consists of a supporting stand 15 of telescopic form so that it may be extended to the desired height and the table portion is hingedly and adjustably supported upon a lateral arm in order to overhang or extend over a bed or chair beside which the 20 device is placed. The structure is provided with a shelf that is mounted upon the lower portion of the standard to receive books and other articles, and the major portion of said shelf projects upon the side of the standard 25 that is opposite the overhanging table thereby acting as a counter-balance for the latter to prevent its tipping while in use. I have numerous objects in mind, among which are dependability and readiness of operation, 30 durability in construction, simplicity and sturdiness in the formation and arrangement of the parts, and the whole device is arranged, fabricated, and assembled in a novel and economical manner, which permits its being 35 retailed for a reasonable price.

I prefer to accomplish the numerous objects and to carry out my invention in substantially the manner hereinafter fully described and as more particularly pointed out 40 in the claims, reference being made herein to the accompanying drawings that form a part of this specification.

In the drawings:—

Figure 1 is a perspective showing my im- 45 proved stand ready for use.

Figure 2 is a top plan of the counter-balance shelf and showing the arrangement of the supporting feet of the standard.

Figure 3 is an end edge elevation of the ta- 50 ble member.

Figure 4 is a detail showing the assembly of the extensible standard and the means for securing the parts in adjusted positions.

Figure 5 is a detail of the lower portion 55 of the standard and showing the shelf in side elevation.

The drawings are more or less schematic for the purpose of illustrating a typical or preferred embodiment of my invention, and in said drawings similar reference characters 60 have been employed to designate like parts wherever the same appears throughout the several views.

The extensible standard consists of a tube 10 in which an L-shaped rod or tube is telescopedically positioned, the vertical portion 11 of the latter being long enough to extend down into the tube a distance sufficient to permit the horizontal portion or lateral arm 12 to be adjusted to a wide range of vertical positions. To permit the adjustments of the extensible member of the standard the tube 10 is provided with an elongated slot 13 extending longitudinally of the tube to receive the shank 70 of a wing bolt 14 that is screwed into the lower portion of the part 11 of the extension as seen in Fig. 4 which permits the bolt to be loosened to allow the lateral arm 12 to be raised or lowered to the desired plane after which the bolt is tightened to clamp the parts 10 and 11 firmly together. The construction and arrangement of the standard also prevents rotational movement of the parts thereof.

At the base of tube 10 there is a plurality of 85 supporting feet, preferably three in number, for stability, one of which, 15, is of short reach as compared to the others and projects from the side opposite that upon which the arm 12 extends, and the other feet, 16, as seen in Figures 2 and 5 diverge from the standard upon 90 the side below the table, and are considerably longer than the foot 15 so as to assist in preventing the tilting of the structure due to any overbalanced weight on the table. Immediately 95 above the feet there is placed a shelf 17, made from sheet metal and there is a flanged collar 18 secured to the underside of this shelf to surround the opening or aperture made in the plate through which the standard 100 passes, which collar is pinned or otherwise se-

cured to the standard. It will be noted said shelf is not mounted at its center on the standard, but its major portion projects over the short foot 15 so that when books and other heavy articles are placed on this portion of the shelf the same will act as a counter-balance for the table portion that is carried by the arm 12. This wide portion of the shelf is provided with three up-standing walls 19 of sufficient height to retain the books and other articles may be stacked thereon against the walls. The narrower portion of the shelf 17 on the opposite side of the standard is provided with a shallow wall 20 upon which a pivoted arm 21 is mounted in a frictional manner so that the latter may be raised to the position shown in Figure 1 to afford a rest or retainer for newspapers, music sheets, and the like which may be placed between the arm and the standard.

The table portion of the structure is preferably in the form of a metal plate 22 that is suitably mounted upon the arm 12 and the edge thereof which is to be positioned nearest the person using the stand is provided with a lateral flange 23 to afford a rest for a book or magazine when the table is tilted, and there is a spring bar 24, frictionally pivoted upon the plate, that may be moved to a position to engage the leaves of an open book, magazine, or the like and retain the same in a flattened position. This arrangement is obviously quite handy for sick, infirm, or crippled persons as it relieves them of the physical strain or exertion usually required to hold an opened book in the hands for any length of time. An electric bulb is mounted in a reflector socket 25 that is secured by means of a flexible joint 26 to an edge portion of the plate 22 and the conductors 27 therefrom pass through the hollow extensions 11 and 12 and down through the tube 10, from the lower end of which they emerge and lead to any suitable source of electric supply. The reflector socket and the universal joint permits the light to be directed upon the matter on the table and will shield the eyes of the person using the same thereby relieving them of eyestrain.

The table plate is hingedly mounted upon a bracket or bar 28 that projects laterally from the arm 12 of the standard. This bar 28 may be made as a part of the arm, or it may be a separate piece, as shown herein, that is firmly clamped to the arm by means of a substantially U-shaped strap 29, the parallel arms of which are bolted to the upper and lower edges of the bar with its curved intermediate portion partly encircling the adjacent portion of the arm, and in order to provide a rigid construction or assembly the adjacent end of the bar is set into a vertical transverse slot or recess cut in the arm as seen in Figure 3. The table plate 22 is provided with a pair of alining stamped out perforated ears 30 that project laterally from the under-

side thereof and carry a hinge rod 31, which rod intermediate its ends passes through and is retained in a transverse aperture in the supporting bar 28. This permits the hinging or tilting of the table to the desired angle as seen in Figure 1 or the table may be placed flat or horizontal as in Figure 3, in which position its rear will be supported by a block 32. The means for maintaining the table or plate in tilted positions consists of a brace formed of a U-shaped wire rod the parallel arms 33 of which have laterally bent ends that enter bearing holes in a pair of apertured stamped-out lugs 34 disposed in about the same manner as the ears 30 hereinbefore mentioned. The transverse member 35 of the U-shaped brace is adapted to be placed in any one of a plurality of notches 36 made in the upper edge of the bar 28 and thus adjustably maintain the table as desired, and when the table is lowered to a flat or horizontal plane this brace is moved out of engagement with the bar as seen in Figure 3, and the table used in any manner desired. An upwardly and forwardly slanting notch 37 may be made in the lower edge of the bar and as the table is lowered the brace may be moved over the rear end of the bar and positioned in this notch so that when the table is flat the brace will be maintained in this notch as shown in dotted lines in Figure 3.

It is obvious that modifications or changes may be made, and the specific structure herein shown may be altered as desired. The foregoing detailed description and drawings have been given for the purpose of clearness of understanding only, and no unnecessary limitation should be understood therefrom, but the appended claims should be construed as broadly as permissible in view of the prior art.

What I claim:—

1. A utility stand comprising an extensible standard having an upper member having a laterally extending supporting arm, a bar projecting from said arm and having notches in its longitudinal edge, a table plate having ears upon its bottom surface, a hinge-rod connecting said ears and intermediately connected to said bar, and a brace swingingly mounted on said table-plate and adapted to be selectively positioned in said notches, whereby said table-plate may be tilted to different positions and maintained in such positions by said brace.

2. A utility stand comprising a standard, a lateral arm at the upper end thereof having a transverse recess intermediate its ends, a bar having one end seated in said recess and extended laterally from said arm, a U-shaped strap the ends of which are secured to said bar and the intermediate portion of which embraces said arm for clamping said bar to said arm, whereby said bar is immovably

connected to said arm, and a table mounted on said bar.

3. A utility stand comprising a standard, a lateral arm at the upper end thereof having a transverse recess intermediate its ends, a bar having one end seated in said recess and extended laterally from said arm, a U-shaped strap the ends of which are secured to said bar and the intermediate portion of which embraces said arm for clamping said bar to said arm, whereby said bar is immovably connected to said arm, a table mounted on said bar, and devices having operative connection with said bar and table whereby the latter may be maintained in tilted positions with respect to the bar.

Signed at Chicago, in the county of Cook and State of Illinois, this 12th day of January, 1928.
